UNITED STATES PATENT OFFICE.

LAURENCE A. SWEET, OF LOS ANGELES, CALIFORNIA.

DESIGN FOR A RADIATOR CAP.

Application filed August 27, 1923. Serial No. 7,098. Term of patent 14 years.

To all whom it may concern:

Be it known that I, LAURENCE A. SWEET, a citizen of the United States, residing at Los Angeles, in the county of Los Angeles and State of California, have invented a new, original, and ornamental Design for Radiator Cap, of which the following is a specification, reference being had to the accompanying drawing, forming part thereof.

Figure 1 is a front elevation of a radiator cap, showing my new design;

Fig. 2 is a rear elevation;
Fig. 3 is a plan view; and
Fig. 4 is an end view.

It is a particular feature of my design that the balls on the ends of the arms and the top of the latch be of a color contrasting with the rest of the cap.

I claim:

The ornamental design for a radiator cap, substantially as shown.

LAURENCE A. SWEET.
